[57] **CLAIM**

The ornamental design for a cart, as shown and described.

DESCRIPTION

FIG. 1 is a perspective view of a cart showing my new design;

FIG. 2 is a front elevational view thereof, the rear being a mirror image of that shown;

FIG. 3 is a side elevational view thereof, the opposite side being a mirror image of that shown;

FIG. 4 is a top plan view thereof;

FIG. 5 is a bottom plan view thereof;

FIG. 6 is a perspective view of a second embodiment of a cart showing my new design;

FIG. 7 is a front elevational view of FIG. 6, the rear being a mirror image of that shown;

FIG. 8 is a side elevational view of FIG. 6, the opposite side being a mirror image of that shown;

FIG. 9 is a bottom plan view of FIG. 6; and

FIG. 10 is a top plan view of FIG. 6.
